UNITED STATES PATENT OFFICE.

JOHN M. O'BRIEN, OF WEST WINFIELD, NEW YORK.

GAS-ENGINE.

1,283,276.

Specification of Letters Patent. Patented Oct. 29, 1918.

Application filed October 8, 1917. Serial No. 195,428.

To all whom it may concern:

Be it known that I, JOHN M. O'BRIEN, a citizen of the United States, residing at West Winfield, in the county of Herkimer and State of New York, have invented certain new and useful Improvements in Gas-Engines, of which the following is a specification.

This invention has relation to internal combustion engines, and more particularly to two-cycle engines, and has for an object to provide an engine of this type embodying a plurality of cylinders having a common crank casing therebetween.

Another object of the invention is to provide an internal combustion engine of the two-cycle type embodying means including a valve located between the cylinder and the crank case, to permit compression of the charge to take place between the under side of the piston and said valve means.

In addition to the foregoing my invention comprehends improvements in the details of construction and arrangement of the parts to be hereinafter more fully described and particularly set forth in the appended claim.

In the accompanying drawings in which similar and corresponding parts are designated by the same characters of reference throughout the several views in which they appear:

Figure 1, is a view in side elevation of a two-cycle internal combustion engine embodying my invention.

Fig. 2, is a view in vertical section taken transversely through one of the cylinders of the engine and

Fig. 3, is a horizontal transverse section taken on the line 3—3 of the preceding figure.

With reference to the drawings 10 indicates a crank casing and 11 a crank shaft journaled therein having an offset 12. A plurality of cylinders 13 are mounted on the 45 crank case in the usual manner.

Each cylinder is provided with an annular groove 14 at the lower end thereof adjacent the point of connection of the cylinder with the crank case. A ring 15 is inserted 50 in the annular groove and rests against a shoulder 16 formed by the provision of the groove, the inner surface of the ring being curved to conform to the surface of a sphere. A valve 17 in the nature of a substantially 55 semi-spherical hollow member is located in

the lower end of the cylinder and is designed to snugly fit the curved inner surface of the ring 15 as illustrated. A second ring 18 is then inserted in the lower end of the cylinder and is similarly formed with a 60 curved inner surface to conform to the surface of the valve 17 whereby said valve is held in place and at the same time is permitted to rotate.

The piston, indicated at 19, is provided 65 with a connecting rod 20 which extends through the cylinder into the crank case and is connected to the offset of the crank shaft. The connecting rod extends through a substantially spherical bearing member 21 70 which is held within an opening 22 in the spherical valve 17, the surface of the opening being curved to conform to the curved surface of the member 21, a ring 23 being then inserted in the opening to engage the spherical member 21 to prevent displacement thereof. The rod 20 is designed for sliding movement in the spherical member 21. It is to be noted that an opening 24 is formed in the wall of the valve 17 adjacent the 75 shoulder 16 of the cylinder so that the opening may serve at times to establish communication between the cylinder and the interior of the crank casing when the valve 17 is rotated for that purpose. The flat side of the 80 semi-spherical valve 17 is formed with an elongated opening 25 through which the connecting rod 20 extends. Said connecting rod being rectangular in cross section so as to prevent rotation of the spherical member 17 85 relative to said connecting rod. A carbureter, indicated at 26 may be placed in communication with the interior of the crank casing whereby the vapor generated by the carbureter may be drawn into said crank 90 casing during operation of the engine.

An inlet port 27 is provided in one wall of the cylinder adjacent the head end, and a port 28 is provided in the cylinder wall at a point adjacent the opposite end thereof, located so as not to be covered by the piston when the same is at its lowermost position. The ports 27 and 28 are then connected by means of a bypass tube 29. An exhaust port 30 is located adjacent the head end of the 105 cylinder in the usual manner.

During rotation of the crank shaft, it will be apparent that owing to the oscillatory movement of the connecting rod, and the universal connection thereof with the semi- 110

spherical valve 17 said valve will be rotated through a partial revolution during each complete revolution of the crank shaft. This motion of the semi-spherical valve will have 5 the effect to uncover the opening 24, which at times is covered by the ring 14, so as to establish communication between the interior of the crank case and the cylinder below the piston.

10 Therefore, in operation, and assuming that the piston is moving on an upward stroke, the port 24 of the semi-spherical valve will be uncovered so as to permit a charge to be drawn from the interior of the crank case 15 through the port 24 into the space of the cylinder below the piston. On the next downward stroke of the piston the port 24 will be covered, and the vapor within the cylinder below the piston will be compressed 20 until the top edge of the piston uncovers the intake port 27. The charge is then permitted to enter the upper end of the cylinder through the by pass 29, so that a subsequent turn of the piston in an upward direction 25 will compress the charge within the upper end of the cylinder and upon an explosion of the charge, the piston will descend, exhausting the burnt gases through the exhaust port 30 when said port is uncovered by the 30 piston. The downward movement of the piston under the influence of the explosion serves to compress the charge below the piston which had entered upon a previous upward movement of the cylinder and this operation is repeated, a power stroke taking 35 place every revolution of the crank shaft in the usual manner of a two-cycle engine.

Thus, each cylinder is capable of operating independently of the next, although each 40 draws in a charge from the crank casting which is common to all cylinders and which is in communication with the carburetor. If desired the offsets of the crank shaft may be

in opposed relation, so that when two cylinders are provided, a power stroke is obtained upon every half of a revolution of the 45 crank shaft. The number of cylinders may be multiplied, and the offsets of the crank shaft arranged in any relation desired.

While I have illustrated and described my 50 invention with some degree of particularity I realize that in practice various alterations 55 thereover may be made, and I therefore desire to reserve the right and privilege of changing the form of the details of construction, or otherwise altering the arrangement of the correlative parts without departing from the spirit of the invention or the scope of the appended claim.

Having thus described my invention what 60 I claim as new and desire to secure by Letters Patent is:-

In a two-cycle internal combustion engine, having an annular groove formed at the base of the cylinder, the combination of a pair of 65 rings mounted in said groove, said rings having their inner surfaces curved to conform to the surface of a sphere, a semi-spherical hollow valve, between the rings and supported therein for rotation, said valve having a 70 valve opening in one side wall thereof and an opening to receive the connecting rod, a spherical apertured member mounted in said last mentioned opening of the valve, to permit the connecting rod to extend there- 75 through whereby the valve is operated upon oscillation of the connecting rod to uncover the valve opening and permit the entrance of the charge from the crank casing to the cylinder.

In testimony whereof I affix my signature in presence of two witnesses.

JOHN M. O'BRIEN.
